UNITED STATES PATENT OFFICE.

WILLIAM A. SCHROEDER, OF SEATTLE, WASHINGTON.

TRACKER-BOARD-ADJUSTING MECHANISM.

1,203,137.

Specification of Letters Patent. Patented Oct. 31, 1916.

Application filed June 3, 1915. Serial No. 31,823.

To all whom it may concern:

Be it known that I, WILLIAM A. SCHROEDER, a citizen of the United States, and resident of Seattle, in the county of King and State of Washington, have invented certain new and useful Improvements in Tracker-Board-Adjusting Mechanisms, of which the following is a specification.

My invention relates to automatic players for pianos, organs, etc., and consists of improvements in the tracker bars whereby adjustments are automatically made to accommodate variations in the width of the music sheets, particularly such as are caused by variations of atmospheric moisture.

The novel features of my invention will be hereinafter described and particularly pointed out in the claims.

In the accompanying drawings I have shown my invention in its preferred form of construction.

Figure 1 is an elevation of the music and receiving rolls and the operating mechanism therefor, the bellows controlling mechanism being in section. Fig. 2 is the same in plan. Fig. 3 is a view, on a larger scale, showing the bellows controlling mechanism in section, the valves being in different positions from those of Fig. 1. Fig. 4 is a like view to Fig. 3 the valves being differently positioned. Fig. 5 is a horizontal section on the line 5—5 of Fig. 3. Figs. 6 and 7 are side and end elevations of the roll turning and shifting mechanisms. Figs. 8 and 9 are sections taken respectively on the lines 8—8 and 9—9 of Fig. 6. Fig. 10 is a side view of a tracker bar having thereon the devices used by me for adjusting it to compensate for small variations in width of the music sheet.

Fig. 11 is an edge view, with portions in section, of the same parts. Fig. 12 is a side view, partly in section, of one end of the tracker bar. Fig. 13 is a section on line 13—13 of Fig. 10. Fig. 14 is a section on line 14—14 of Fig. 10. Fig. 15 is a section on line 15—15 of Fig. 10. Fig. 16 shows one of the adjustable tracker blocks in perspective.

It has been found by experience, that the music sheets, used in player pianos, vary somewhat in width, according as they are

dry or moist. Being made of paper they readily absorb atmospheric moisture and become wider, contracting when the moisture is expelled.

As the proper functioning of the machine demands a proper registration between the holes in the paper and the ports in the tracker board, and the tracker board is not similarly affected by varying moisture conditions, the holes in the paper will not, all of them at all times, register with the holes or ports of the tracker board.

I have also found that the variation in the spacing of the holes in the paper roll, due to absorption and expulsion of moisture, occurs in much greater degree in the marginal parts of the roll, than in the central part, as, when rolled, the central part of the roll is more protected from atmospheric moisture than its ends. To remedy this, I make a tracker board in which a considerable number of the ports, at each end thereof, are subdivided into small units, these being proportionally adjustable lengthwise the tracker board, to vary the spacing between them, to thereby increase or decrease the total length of the line of ports.

The construction of the tracker board, as herein shown in detail in Figs. 10 to 15, is that which is preferred. The board 1 is, or may be, of usual or standard construction, except as otherwise indicated. The tracker board and the arrangement of the ports 10, throughout a considerable distance at each side the center of its length, are of standard construction.

For a distance at each end, the ports are in blocks, 2, of which one is shown detached, in perspective, in Fig. 16. The blocks, as shown, each contain two ports. While it is desirable to keep the number of ports in each block small, the number might be somewhat increased.

The tracker board 1, has a guide slot at each end, fitting closely over the assembled blocks 2, and of a length to permit the necessary adjustment. These blocks are so constructed and mounted as to be easily movable lengthwise the tracker board, while maintained in parallel position. Any construction which secures this result may be

used. That shown and which I now prefer, is the following.

The blocks 2 are square, or rectangular, in cross section and are cut down at each end 5 to form the tenons, or webs, 20 and shoulders 21. The rabbets thus formed receive the guide bars 11, which are secured to the tracker bar 1. These blocks have nipples 23 at one end, for connection of flexible hose 24, 10 which lead to the air-exhausting mechanism. It also has channels or ports extending from these nipples to the opposite end, the ports or tracker holes 10, 10, being the terminals thereof. These blocks are connected to be 15 moved lengthwise the tracker board by some mechanism which will move them all simultaneously and proportionally; that is, the outermost block will receive the maximum movement and the innermost the least, 20 the others between being moved amounts which vary regularly, each from the next adjacent in the series, by the same amount. The means chosen and herein illustrated for securing this are as follows:

25 A series of levers 3, extend lengthwise the blocks 2, one end of each lever being mounted upon a fixed pivot 32, and connected by a pivot 31, located inward from said end, to its particular block 2. For convenience in 30 assembling, the end pivots 32 are supported from bars 33, and to allow for the slight lateral and unequal separation due to the swing of the levers, the bar 33 is secured only by pivoting at 33^b, at the inner end of the 35 series.

Each lever is connected with the next in the series by a link 30, this connection being closer to the pins 32 upon which the levers swing, for that lever of any pair which is 40 nearest the outer end of the tracker board, than its connection with the lever inward hereof. This places the connecting links 30 at an angle. The outermost lever of the series is the one to which movement is primarily 45 communicated. By reason of the different distances at which the links 30 are connected to these levers, the movement of successive blocks 2 is cumulatively reduced.

I have shown four sets of levers 3, employed for each set of blocks 2, a lever being connected to each end of each block, this being duplicated at each side. At the outer end of the series a four armed yoke 34 has an arm connected, each with its respective 55 lever 3, and an arm 36 which is connected with a rod 35.

Outward of the slot in the tracker bar which receives the blocks 2, is a slot which receives the tracker block 4, which is directly connected with the bent end of rod 35. 60 A guide pin 41 may be employed to hold it in correct position. This block has a port or hole 40, which is designed to register with the edge of the music roll and to be auto-

65 matically shifted to compensate for the slight variations in width of the roll. These blocks 4 would be shifted outward or inward in conformity with the movement of the blocks 2. A hose 25 connects its port with the air operating mechanism.

70 The above parts are duplicated at each end of the tracker bar. A short link 37 connects the shortened rod 35' of one end with the lever 42, at one side of its pivot 43, while the long link 35 connects the opposite blocks 4, with lever 42, at the opposite side of its pivot. Lever 42 is actuated by link 44, and this by bellows 45 and spring 46.

75 The music roll 12 and receiving spool 13, have their pivot axes, at one end, mounted to turn in spring held and axially yielding sockets 14, to facilitate their insertion and removal. Their other ends are fitted upon short shafts 15, which have thrust bearings 80 against set screws 16, carried by levers 17, pivoted at one end, as at 18, and with their other end engaged by a shifting member. Such shifting member, as shown, consists of 85 an eccentric 50 mounted on shaft 5 and engaging the end of lever 17. This shaft has a crank arm 51, which is actuated through a rod 52, or in any other suitable manner. By 90 this mechanism the rollers may be shifted to cause the roll to register accurately with the ports in the tracker bar.

95 The above roll shifting mechanism may be actuated by any suitable device, as the double acting bellows 55, 56, which is of a standard construction and acts through link 54 and lever 53, upon rod 52. The action of these 100 parts is controlled by the ports or tracker holes in the blocks 4, in accordance with the usual practice, except as to the movable character of these blocks.

The mechanism connecting the rolls 12 and 13 to turn them, shown in detail in Figs. 6 and 7, is of old construction. Any suitable mechanism which properly connects these rolls may be employed.

105 The double acting bellows 55, 56, by which the rollers 12, 13 are shifted, is, in construction and operation, of standard type. It has ports 57, 57' controlled by double acting valves 58, 58' connecting with an exhaust chamber 59 and a free air space 59'. The air 110 in exhaust chamber 59 is removed through a pipe 70' which connects with the exhausting mechanism used to operate devices of 115 this character.

The mechanism for controlling the bellows 45, by which the adjustable tracker blocks 2 are adjusted, is as follows, as illustrated in Figs. 1 to 6.

120 An exhaust or vacuum chamber is provided consisting of lower section 7 and upper section 7' connected by channels 7" and exhausted through pipe 70. The block 93, which separates the parts 7 and 7', has there-

in port 77, which communicates with free air, and ports 78 and 79. The port 78 connects two chambers formed therein, the one at the bottom containing a diaphragm 73 which may be seated to close port 78, and the one at the top containing diaphragm 76, which may be seated to close port 79. Port 79 also connects with another recess which contains a diaphragm 9, which controls valve 90 and port 91, this communicating, through port 92, with the bellows 45. A port 84 connects chamber 95, back of diaphragm 72, with exhaust channel or port 8 and a port 85 connects chamber 94, back of diaphragm 71, with exhaust channel or port 81. A bleed hole 88, connects port 79 with the exhaust chambers 7, 7'. Bleed holes 80 and 82, connect exhaust chamber 59 with ports 8 and 81, respectively. These bleed holes are, in each case, of much less size than the ports with which they are connected, from which it follows that the pressure upon the side toward the exhausting mechanism, is less than upon the other side, so long as the supply of air furnished to the outer passages is in any considerable amount.

The roll shifting mechanism, shown in Figs. 6 to 9, is controlled by the double acting bellows 55, 56, the action of these bellows being controlled in a well known manner. The extension 87 of port 8, leads to one roll shifting port in the end block 4, and the extension 86 of port 81, leads to the like block at the other end. A stoppage of air supplied through these ports, by their being covered by the edge of the roll, lowers the pressure in these ports, causing the diaphragm 83 or 83', as the case may be, to drop, thus dropping the corresponding valve 58 or 58', placing the port 57 or 57', in connection with the exhausting mechanism, thus causing a reduction of the air pressure in the side of the bellows connected therewith and moving the partition wall 54' over to this side and thus, through link 54 and connected mechanisms, shifting the roll to secure its being positioned centrally of the two ports of blocks 4.

The position of parts shown in Fig. 4 is that where the two ports 40 are differently positioned relative to the edges of the roll, the port 40 connected with port 8 being covered, while the other port 40, which connects with port 81, is uncovered. The reduction of pressure in port 8, due to the stoppage of the supply of air therein and the withdrawal of the contained air through bleed hole 59, causes the valve 58 to open, withdrawing the air from the side 55 of the bellows and moving the partition 54' to this side, until the rolls have been shifted so that the opposite holes 40 are equally uncovered.

Normally the ports 8 and 81 are in com-

munication with the atmosphere through the ports 40, which produces pressure on diaphragms 71 and 72, to force the valve buttons 73 and 74 against the diaphragms 75 and 76, to thus close the passages 78 and 79.

With the pressure in port 8 reduced, by reason of its connected port 40 being covered by the edge of the music sheet, the pressure acting through port 84 in chamber 95, will be relieved and any air pressure in port 78 will be able to pass through port 79 to diaphragm 9, to raise it and place the port 92 in connection with the exhausting mechanism. If, however, the opposite port 40 is uncovered, so that air may enter ports 81 and 85, this will raise diaphragm 71, force diaphragm 75 down to close port 78, thereby preventing flow of air therethrough. One or the other of the diaphragms 71, 72, will be acted upon by air received through its connected port 40, thereby preventing flow of air to port 79, unless both ports 40 are closed, in which case air may freely enter to act on diaphragm 9. Such position of parts is shown in Fig. 3. When this occurs, free air obtains access to the under side of diaphragm 9, while the other side is exposed to the exhausted chamber 7'. In consequence, valve 90 is raised, establishing an exhaust connection through ports 91 and 92, with bellows 45, to cause it to collapse and move the bar 44. This results in the separation of the blocks 4, and with this, the proportional separation of the blocks 2. As the ports 40 are uncovered, air entering therein will have access through ports 86, 85 and 87, 84, to the outer surfaces of the diaphragms 71, 72, until this pressure approaches that in chamber 7, 7' whereupon valves 73, 74, will be closed and equilibrium of pressures will be established between chamber 7' and port 79, causing valve 90 to drop and cut the bellows 45 off from the exhausting mechanism.

The length of the adjustable section of tracker blocks 2, may be made greater or less than has been shown. The mechanism shown by which these blocks are moved, is that which is now preferred by me, but it is evident that other constructions may be used to secure the same result. I do not therefore desire to be limited to the use of this specific mechanism.

The method of controlling the operation of the adjusting mechanism, leaves the roll shifting mechanism free to act without affecting the mechanism for adjusting the tracker blocks. The roll shifting mechanism is actuated upon the covering of either one of the end ports or holes 40, while the block adjusting mechanism is actuated only upon the covering of both the holes 40. This effect is produced by placing the valve which controls the bellows 45, itself under the control of the two valves 72 and 73, the latter being

controlled, each by the covering of its respective tracker hole 40 by the edge of the music sheet.

Air may be supplied to bellows 45 through 5 a port and pipe connection 92' with a relief port 92" located just within the ports 40. This relief port would be covered while a music sheet is in place and uncovered when the sheet is removed. Leakage past valve 90 10 would soon fill the bellows 45 after stoppage of the air pump.

Having thus described my invention, what I claim as new, and desire to secure by Letters Patent of the United States of America, 15 is:—

1. The combination with a roll-centering mechanism, of a tracker board provided with means for variably spacing certain of the tracker holes, and means for controlling 20 the spacing of the tracker holes by the roll centering mechanism.

2. The combination with a tracker bar having members adjustable lengthwise the bar, an outer of said members at each end 25 containing the roll centering holes, those inward of these members containing ordinary tracker holes, and means connecting all of said adjustable members to secure proportional 30 adjustment therebetween.

3. The combination with a tracker bar having members adjustable lengthwise the bar, an outer of said members at each end containing the roll centering holes, those inward of these members containing ordinary 35 tracker holes, means connecting all of said adjustable members to secure proportional adjustment therebetween, and means controlled by the music roll through the roll-centering holes for actuating said mechanism.

4. A tracker bar having a central series of fixedly positioned tracker holes, movable units outwardly therefrom containing the remainder of the tracker holes, movable 45 members containing the roll-centering holes, and means connecting all of said movable members to move them in harmony.

5. In a tracker bar in combination, a series of blocks mounted for adjustment 50 lengthwise the bar and containing therein tracker holes, and a series of levers each connected with another and with said blocks to secure proportional and unequal separation of the blocks.

6. In a tracker bar in combination, a series of blocks mounted for adjustment lengthwise the bar and containing therein 55 tracker holes, and a series of levers connected by one end to fixed pivots and having a pivot connection, each with its respective 60 tracker block, and links connecting said levers in series, the points of connection of said links with the actuating levers being at different distances from their fixed pivots

than their points of connection with the 65 actuated levers.

7. A tracker bar having a slot in each end which includes the positions for a series of tracker holes extending from the ends inward, a series of blocks mounted in said 70 slots and adjustable lengthwise the bar, each block containing its quota of tracker holes, a lever for each block having a fixed pivot and a pivot connecting it with its block.

8. In a device of the character described, 75 in combination, a tracker bar, two tracker members adjustable lengthwise the bar and each having a hole adapted to register with the edges of the music, a pneumatically operated mechanism for centrally positioning 80 the music sheet controlled by the position of the said tracker holes relative to the edges of the music sheet, a pneumatically operated mechanism for adjusting said tracker members lengthwise the bar, a valve controlling 85 the action of said last named mechanism, a member controlling said valve and ports adapted for connecting it with an exhaust chamber and with the free air to oppositely 90 actuate the valve, and a pair of valves placed in series to control one of said ports and each having a controlling connection with its respective one of the adjustable 95 tracker holes.

9. A mechanism for controlling a pneumatically operated device comprising a normally closing valve controlling the air connection therewith, a pneumatic actuator for said valve, an air connection with both sides of said actuator, the connection which acts 100 to close the valve being choked or relatively restricted in area, the same side having a connection with the free air, two valves controlling said free air connection, and means for controlling said latter valves each from 105 its respective source.

10. In a device of the character described, adjustable members containing tracker holes, a pneumatically operated device for actuating 110 said adjustable tracker members, an exhausting mechanism connected with said actuating device, a valve controlling said connection, a diaphragm controlling the position of said valve, an exhaust mechanism having a free connection with one side 115 of the diaphragm and a restricted connection with the other side thereof, said latter side having a connection with the free air, and two diaphragm controlled valves controlling said free-air connection, and means 120 for independently controlling each of said two valves to open them by the reduction in pressure of the air back of the said adjustable tracker holes.

11. In a device of the character described, 125 in combination, a tracker bar, tracker members at each end thereof adjustable lengthwise the bar and each having a tracker hole

adapted to register with the edge of the music sheet, means for adjusting said tracker members, a pneumatically operated actuating device therefor, a valve controlling the application of the air to said pneumatic device, and means for controlling said valve comprising an air supplying conduit, two valves controlling said conduit, means nor- mally acting to hold said valves closed and opening means for said valves comprising 10 an air connection from each to its respective one of the ports leading from the adjustable end tracker holes.

Signed at Seattle, Washington, this 20th day of May, 1915.
